UNITED STATES PATENT OFFICE.

WILLARD JONES, OF AUBURN, MAINE.

COMBINATION-TOOL.

No. 896,117.

Specification of Letters Patent. Patented Aug. 18, 1908.

Application filed August 28, 1907. Serial No. 390,506.

To all whom it may concern:

Be it known that I, WILLARD JONES, a citizen of the United States, residing at Auburn, in the county of Androscoggin and 5 State of Maine, have invented a new and useful Combination-Tool, of which the following is a specification.

This invention relates generally to combination tools, and more particularly to one 10 adapted to be carried, conveniently, in the pocket of the owner.

The object of the invention is to provide a combination tool which shall embody in a compact attractive form, a key ring, a screwdriver, a bottle cap remover, a cigar cutter, a cork screw, and bottle wire remover, all the parts being so constructed and disposed relatively to each other that in the use of one 20 there will be no interference with or by the others.

With the above and other objects in view as will appear as the nature of the invention is better understood, the same consists in the 25 novel construction and combination of parts of a combination tool, as will be hereinafter fully described and claimed.

In the accompanying drawings forming a 30 part of this specification and in which like characters of reference indicate corresponding parts, Figure 1 is a view in perspective of a combination tool constructed in accordance with the present invention, showing the position that the cork screw will occupy in use. Fig. 2 is a view in side elevation. Fig. 35 3 is a view in vertical longitudinal section, taken on the line 3—3 of Fig. 2, and looking in the direction of the arrow thereon. Fig. 4 is a transverse sectional view, taken on the line 4—4 of Fig. 2, and looking in the direction of the arrow thereon.

The implement embodies a stock or handle 1 with which all of the operative parts are combined. The stock is preferably constructed of a strip of resilient metal and is 45 provided at one end with an annular head 2 that is cleft at 3 to provide a key ring. At the other end of the stock is formed a hook-shaped extension 4 that constitutes a bottle wire remover, a portion of the outer edge of 50 which is beveled at 5 to form a screwdriver. The intermediate portion of the stock is turned to form two guides 6 and 7 between which is adapted to work a plate 8 having one end beveled and sharpened to provide a 55 cigar cutter 9, and its other end curved or

bent to provide a bottle cap remover 10 which also constitutes the means for operating the cutter. Each of the flanges is provided with a lug 11 and 12, the two lugs being disposed in transverse alinement and being adapted to operate as stops to limit the outward movement of the combined cigar cutter and bottle cap remover. The stock is provided adjacent to the hook 4 with an orifice 13 through which the tip of the cigar will 60 be inserted when it is to be cut by the knife 9.

Pivotedly connected with the stock at a point between the key ring and the flanges is a cork screw 14, of the usual or any preferred construction, the attachment of which with the stock is secured by bending the shank of the cork screw at right angles to its length at 15, and projecting the arm thus formed through an orifice in the stock provided for it, the end of the arm being upset, as at 16, to 75 prevent its disconnection from the stock.

In order to hold the cork screw at right angles to the length of the stock and in position to operate upon a cork, the flange 7 is provided with an extension 17 under which 80 the shank of the cork screw will pass, as shown in Fig. 1, a seat 18 being formed in the extension for the purpose of holding the cork screw against movement.

The normal position of the cork screw will 85 be lengthwise of the stock, as shown in Figs. 2 and 3, and in order to protect the pocket of the wearer from damage by the former, a cap 19 is provided within which the cork screw will fit, as clearly shown in Fig. 3.

The extension or keeper 17 is of peculiar 90 advantage and utility, inasmuch as by merely swinging the cork screw to one side it will be retained in operative position and thereby obviate the necessity of employing spring latches or the like; such as are commonly used.

The tool herein described will be found 95 highly efficient and durable in use, and will in a compact space provide a plurality of implements all of which will be found at times of service.

What is claimed is:

1. A combination tool embodying a stock having longitudinal guides one of which is 105 extended to provide a keeper, a cigar cutter engaging the guides and having a curved extension constituting a means for operating the cutter and also a bottle cap remover, and a cork-screw having a pivotal connection with 110

the stock and being adapted to engage with the keeper to hold it at right angles to the length of the stock.

2. A combination tool embodying a stock 5 provided with an orifice and with longitudinal guides, and a cigar cutter engaging the guides and having a curved extension constituting a means for operating the cutter and also a bottle cap remover, the cutter 10 being adapted to coact with the orifice in severing the tips of cigars.

3. A combination tool embodying a stock provided with an orifice and with longitudinal guides, a cigar cutter engaging the guides 15 and having a curved extension constituting a means for operating the cutter and also a bottle cap remover, the cutter being adapted to coact with the orifice in severing the tips of cigars, and stops carried by the guides to 20 limit the movement of the cutter in one direction.

4. A combination tool embodying a stock provided with an orifice, and with longitudinal guides one of which is extended to provide 25 a keeper, a cigar cutter engaging the guides and coacting with the orifice and having a curved extension constituting a means for operating the cutter and also a

bottle cap remover, stops carried by the guides to limit the movement of the cutter in 30 one direction, and a cork-screw having a pivotal connection with the stock and being adapted to engage with the keeper to hold it at right angles to the length of the stock.

5. A combination tool comprising a stock 35 provided with longitudinal guides, one of which embodies a keeper, a bottle cap remover held in place by the guides, and a cork screw pivotally connected with the stock and adapted to engage the keeper.

6. A combination tool comprising a stock provided with longitudinal guides, one of which extends beyond the other to form a keeper and is provided with a seat, a bottle cap remover held in place by the guides, and 45 a cork screw pivotally connected to the stock and adapted to engage the seat thus to be held at right angles to the length of the stock when in use.

In testimony that I claim the foregoing as 50 my own, I have hereto affixed my signature in the presence of two witnesses.

WILLARD JONES.
